UNITED STATES PATENT OFFICE.

FREDERICK TEED MURDOCH, OF BELFAST, IRELAND.

SKID.

1,115,721.

Specification of Letters Patent.

Patented Nov. 3, 1914.

Application filed November 22, 1913. Serial No. 802,434.

To all whom it may concern:

Be it known that I, FREDERICK TEED MURDOCH, subject of the King of Great Britain and Ireland, and resident of Belfast, in the 5 county of Antrim, Ireland, have invented certain new and useful Improvements in Skids, of which the following is a specification.

My invention relates to improvements in 10 portable skids for use in loading and unloading vans, carts, lorries and the like and for other similar purposes, the object being mainly to provide a device in which the goods being dealt with can be raised from 15 the ground on to the vehicle or platform or be lowered therefrom to the ground by mechanical means and so conserve the energy of the person dealing with the loading and unloading of the goods.

20 My invention consists essentially of a skid frame the upper end of which is adapted to be clamped to or to be reared against the platform or the like to or from which the goods are to be raised and lowered; a traversing carriage device to support the goods; 25 means for adjusting parts of the carriage device with relation to the skid frame and means for raising and lowering the carriage in the skid frame.

30 My invention will be fully described with reference to the accompanying drawings in which,

Figure 1 is a front elevation of a portable skid device constructed in accordance with 35 my invention, Fig. 2 side elevation of same, Fig. 3 front elevation of the movable carriage, Figs. 4 and 5 side elevations of the carriage with the parts in different positions, Fig. 6 front elevation of the clamping 40 device and rope guide, Fig. 7 rear elevation of same, Fig. 8 side elevation of the clamping device, Figs. 9 and 10 side elevations of a modified form of the movable carriage showing the parts in two different positions, Fig. 11 front elevation of same, Figs. 12 45 and 13 side elevations of a further modification of the movable carriage showing the parts in two different positions, Fig. 14 front elevation of same, Fig. 15 side elevation of 50 a still further modification of the movable carriage and Fig. 16 partial sectional front elevation of same, Fig. 17 plan to an enlarged scale showing part of the rope guiding arrangements for the hoisting device, Fig. 18 partial front elevation of same, Fig. 55 19 front elevation showing a slightly modified

fied form of the hoisting arrangement, Fig. 20 side elevation of same, Fig. 21 side elevation to an enlarged scale of a modified form of means for adjusting the movable 60 carriage shown in Figs. 15 and 16, Fig. 22 side elevation of a modified form of the skid frame and means for adjusting two of its main parts, Fig. 23 front elevation to an enlarged scale showing the detail mechanism 65 for adjusting the parts shown in Fig. 22, such mechanism being in the adjusted position and Fig. 24 similar view to Fig. 23 with the parts in process of adjustment.

In accordance with my invention and referring particularly to Figs. 1 to 8 I construct the portable skid from two side frames *a* of channel section with the open sides directed inwardly so as to face each other. The upper ends of the frames are 70 curved and cut away at *b* near the extreme ends to provide gaps and projections *c* which pass behind the flanged edge *d* of a lorry or other platform to or from which the goods are to be raised or lowered. The 75 lower ends of the frames are adapted to rest on the ground and are stayed together transversely by cross rails *e*.

In conjunction with a frame arranged as aforesaid I employ a movable carriage adapted to receive the goods to be raised or lowered, such carriage having side frames *f* connected together by transverse stays *g*. The side frames support rollers *h* fitting freely within the grooves of the skid frames 90 *a*. Projecting from the lower stay of the carriage are two levers *i* pivoted on the aforesaid stay and having short arms *j* at their rear ends which are bent upwardly. The forward ends of the arms or levers *i* 95 may be stayed together if required and be arranged as a platform if necessary. Where barrels are to be hoisted or lowered as shown in Fig. 2 the arms may be somewhat hollow on their upper edges. As the skid frame *a* 100 may require to be arranged at different angles to the horizontal depending upon the height of the platform to which the goods are to be lifted, I arrange to adjust the levers *i* with relation to the skid frame so 105 that such levers may retain a horizontal position or be slightly higher at their free ends than at the points where they are pivoted to the frame so as to more easily retain the goods upon the carriage. This adjustment is carried out in Figs. 1 to 5 by eccentrics *k* mounted upon studs *m* carried by the 110

side frames *f* of the carriage. The eccentrics may be rotated by hand wheels *n* secured to them or by levers. Figs. 4 and 5 show respectively the extremes of adjustment of the 5 parts. In Figs. 9 to 11 the adjustment is carried out by connecting the two levers *i* by a cross bar *o* from which projects upwardly a central arm *p* provided with a tapped hole to receive a screw *q* whose forward end bears against one of the cross bars or stays *g* of the carriage frame. The screw can be adjusted by a hand wheel *r* or lever. Figs. 9 and 10 show the extremes of adjustment. Figs. 12 to 14 show another method 10 of adjustment in which the short arms *j* of the levers *i* are coupled by a stay bar *s* on which is freely mounted the boss of a screw *t* the free end of which passes easily through a slot in the upper transverse stay *g* of the carriage frame. The screw carries a rotatable nut *u* by actuating which the levers *i* may be adjusted. Figs. 12 and 13 show the 15 extremes of adjustment respectively. The side frames *f* in this modification are curved 20 forward to enable the last named arrangement to be adopted. Figs. 15 and 16 show a further modification of the carriage in which the levers *i* are connected to a cross bar *o* also provided with a central arm *p* as in Fig. 11 25 and with a similar arrangement of screw *q* except that the latter passes through a pivotally mounted nut *v* carried by the upper end of the arm *p*. This arrangement enables 30 the parts to operate freely and to adjust 35 themselves readily to the changed condition. A somewhat similar arrangement to that in Figs. 15 and 16 is indicated in Fig. 21 except that the screw is passed through a tapped hole in the arm *p*, this latter arrangement 40 only differing from that shown in Figs. 9 to 11 by the connection of the arm *p* with the cross bar *o*.

In Figs. 22 to 24 the levers or arms *i* are secured to the side frames *f* by the devices 45 shown in Figs. 23 and 24. The side frames are provided with a fixed boss *u* provided with a ring of teeth *x* while each lever *i* is provided with a similar fixed boss *y* having corresponding teeth. The parts are secured 50 together by a bolt *z*. Fig. 23 shows the parts all locked together by the bolt with the teeth in engagement while Fig. 24 shows the bolt slacked back and the teeth out of engagement so that the arms *i* can be raised 55 or lowered about the bolts as pivotal centers to the required angle, the parts being afterward locked together as in Fig. 23. A further feature of the skid frame shown in Fig. 22 is that its upper end is not provided 60 with the clamping device to be hereinafter described, such upper end merely resting upon or against the goods platform. The lower end of the skid frame is provided at each side with an extending foot 2 bent 65 downwardly at its free end 3 so as to engage

with the ground and so form a forward support in addition to the extreme end of the main skid frame. The extending feet may be coupled together by one or more cross stays and may be adjusted in relation to the 70 skid frame in a similar way to the levers or arms *i*, that is to say, by the arrangement shown in Figs. 23 and 24.

In order to clamp the upper end of the skid frame to the lorry or other platform 75 I bolt to the upper cross stay *e* a bracket 4 to the rear side of which is pivoted a screwed link 5 carrying a rotatable nut or tapped lever 6 above which is located freely on the screw a clamping arm 7. By operating the 80 nut or lever the clamp acts in conjunction with the extreme upper end of the skid frame to fix the latter to the platform. The bracket 4 is provided with an extension 8 to prevent the screw and clamp swinging 85 forward and with a further extension 9 forwardly of the bracket to receive a pin 10 on which is mounted a guide rope pulley 11 connected with the hoisting apparatus.

The hoisting apparatus consists in Figs. 90 1 and 2 of a winch handle 12 fixed to a roller or winding barrel 13, the barrel or its shaft carrying a ratchet wheel 14 which can be held in any required position by a pawl 15. One end of the hoisting rope for lifting and 95 lowering the goods carriage is fixed to the barrel 13, then passed over a pulley 16 mounted on a stationary spindle 17. The rope then passes downward and around a groove in a hoisting block 18 pivoted to one 100 of the stays *g* of the carriage. The rope then passes upward and around a second pulley 19 and thence downward to the block to which it is attached. It will therefore be seen that by turning the winch handle 105 clockwise that the goods carriage along with its load can be raised to the platform level. The shape of the skid frame enables the movable carriage to pass easily around its curved portion so as to tip the goods on to 110 the platform in the manner indicated in Fig. 20. Goods may be lowered by turning back the pawl of the winch mechanism and rotating the winding barrel in the opposite direction. 20 is a guide roller for the hoisting 115 rope 21.

In Figs. 17 to 21 the hoisting rope is arranged in a slightly modified form more with the object of distributing the strains of lifting and lowering at each side of the 120 center of the movable carriage. With this object in view the hoisting rope 21 passes from the winch barrel as before around a system of three pulleys 22 the upper one of which is horizontal. The rope passes from 125 the latter downward and under two grooved pulleys 23 arranged on caster brackets 24 pivoted on the carriage frame, said brackets adapting themselves automatically and freely to any position assumed by the carriage. 130

The hoisting rope passes from the second of the two caster pulleys upwardly thence around a system of pulleys 25 similar to 22 and thence downward to the carriage to 5 which it is attached. The winch arrangements are otherwise the same as in Figs. 1 and 2.

The arrangements hereinbefore described are extremely serviceable for the purpose intended.

What I claim as my invention and desire to secure by Letters Patent is:—

In a skid, the combination, with an inclined frame provided with guides, and 15 a carriage for the load, said carriage being movable longitudinally in the said guides and provided at its upper part with a cross stay; of a hoisting block pivoted to the said stay, two supporting levers pivoted to the 20 lower part of the carriage and adapted to rest on the ground, said levers having short

arms which project upwardly in the carriage, adjusting devices for the said levers arranged between the said short arms and the carriage, two stationary guide sheaves 25 journaled at the upper part of the frame with their axis arranged crosswise of the axis of the hoisting block, a hoisting barrel journaled at the middle part of the frame and provided with means for revolving it, 30 and a flexible connection having one end secured to the barrel and its other end secured to the hoisting block with its intervening portions running over the said sheaves and hoisting block.

In testimony whereof I have hereunto set my hand in the presence of two witnesses.

FREDERICK TEED MURDOCH.
